S. L. PORTER, OF ROCHELLE, ILLINOIS, ASSIGNOR TO HIMSELF AND
W. F. EATON, OF THE SAME PLACE.

Letters Patent No. 65,269, dated May 28, 1867.

IMPROVED METHOD OF RAISING AND LEVELLING RAILROAD RAILS.

The Schedule referred to in these Letters Patent and making part of the same.

TO ALL WHOM IT MAY CONCERN:

Be it known that I, S. L. PORTER, of Rochelle, in the county of Ogle, and State of Illinois, have invented a new and improved Device for Surfacing or Levelling Railroad Tracks; and I do hereby declare that the following is a full, clear, and exact description thereof, which will enable others skilled in the art to make and use the same, reference being had to the accompanying drawings, forming part of this specification, in which—

Figure 1 is a side view of my invention as applied to levelling a railroad track.

Figure 2 is a top view of the same.

Figure 3 is a detached view of my adjustable fulcrum.

Figure 4 is a vertical section of the device in the line $z z$, fig. 2.

Similar letters of reference indicate like parts.

This invention relates to a new and improved device for the surfacing or levelling the tracks of railroads. On all railroads it is necessary to keep the track level, and men are constantly engaged in this service. The rails have to be raised and the ties tamped for this purpose. Three men are required to do the work as now performed. By employing my improved device for raising and holding a rail at the proper level one man will be dispensed with, and two men can perform the work as well in the same or less time.

This device is made wholly of iron, and consists of a strong, flat plate, A, about sixteen inches long and eight inches broad, on the upper side of which a vertical slide-plate, B, is fitted to move back and forth lengthwise. It is slotted vertically and longitudinally, so as to work on a guide-block, a, that is made fast to the plate A. The slide-plate B is set nearer one edge of the plate A than the other, as shown in fig. 2; and the front end is made with a series of square steps, c c, upon which the rail rests when lifted for levelling, as hereinafter described. The slide-plate B is made eight inches long, and five high at the forward end. On the broader space, by the side of the slide-plate B, a quadruple fulcrum is pivoted to the bottom plate A, formed of four arms d d, of different heights, as shown in fig. 3. The arms of the fulcrum are made two inches long, the lowest one half an inch high, and the others rising in gradation, half an inch, one above the other.

When used the surfacing-block is applied in this wise: The earth or gravel is first removed with a shovel under the rail to be raised, at some point between the ties, sufficient only to introduce the front end of the plate A under it, until the front end of the slide-plate B touches the rail, when it is set back as far as it will go, as shown in figs. 1 and 2. The crow-bar is shaped with a bend or foot at the bottom, as shown in red, fig. 1. It is then placed with its heel on the lowest fulcrum-arm d, or the next above, if the purchase is required, and the rail is raised to a level with one of the steps c, when, with his foot, the man with the crow-bar pushes the slide-plate B forward till the step passes under the rail, to hold it there if the height is correct. Another man sights the track, and thus the rail may be raised and placed to rest on any one of the steps c on the slide-plate B, the fulcrum being turned to give more or less purchase for lifting the rail, as may be required. The rail being thus supported by the surfacing-block at the required level, it is only necessary to tamp up the ties accordingly, by which method of operation the labor and time required for performing this work are made less than when performed in the usual way, without any provision for a fulcrum but a block or stone, or some accidental support for the crow-bar, nor any means of supporting the rail independent of the lifting-bar, which has to be held; or, the rail is blocked up till the tamping is finished.

Having thus described my invention, I claim as new, and desire to secure by Letters Patent—

The bed-plate A and the slide-plate B, combined with a graduated fulcrum for levelling railroad tracks, constructed and operating substantially as herein described.

The above specification of my invention signed by me this 5th day of December, 1866.

S. L. PORTER.
